[57] **CLAIM**

The ornamental design for a surfboard with transparent window, as shown and described.

DESCRIPTION

FIG. 1 is a top and side perspective view of a surfboard with transparent window embodying my new design;
FIG. 2 is a front elevational view thereof;
FIG. 3 is a top plan view thereof;
FIG. 4 is a left side elevational view thereof, the right side elevational view being a mirror image;
FIG. 5 is a bottom plan view thereof;
FIG. 6 is a rear elevational view thereof;
FIG. 7 is a top and side elevational view of a second embodiment of a surfboard with transparent window embodying my new design;
FIG. 8 is a front elevational view thereof;
FIG. 9 is a top plan view thereof;
FIG. 10 is a left side elevational view thereof, the right side elevational view being a mirror image;
FIG. 11 is a bottom plan view thereof; and,
FIG. 12 is a rear elevational view thereof.
